US0D1105416S

(12) **United States Design Patent** (10) **Patent No.:** **US D1,105,416 S**
(45) **Date of Patent:** **** Dec. 9, 2025**

(54) **INJECTION DEVICE**

(71) Applicant: **Halozyme, Inc.**, San Diego, CA (US)

(72) Inventors: **Kevin Swanson**, Plymouth, MN (US);
Baylor Frantz, Minnetonka, MN (US)

(73) Assignee: **Halozyme, Inc.**, San Diego, CA (US)

(**) Term: **15 Years**

(21) Appl. No.: **29/931,286**

(22) Filed: **Mar. 6, 2024**

(51) **LOC (15) Cl.** **24-02**

(52) **U.S. Cl.**

USPC **D24/113**

(58) **Field of Classification Search**

USPC D24/112-114, 127-130, 133, 186
CPC A61M 5/3156; A61M 5/31591; A61M 5/3155; A61M 5/3157; A61M 5/31501;
A61M 5/14566

(57) **CLAIM**

The ornamental design for an injection device as shown and described.

DESCRIPTION

FIG. 1 is a top perspective view of an injection device showing our new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines depict portions of the injection device that form no part of the claimed design.

1 Claim, 4 Drawing Sheets
